(57) **CLAIM**

The ornamental design for a multi-gang switch socket, as shown and described.

DESCRIPTION

FIG. 1 is a front view showing the OFF status of a multi-gang switch socket of a first embodiment;

FIG. 2 is a right side view of the multi-gang switch socket in FIG. 1;

FIG. 3 is a left side view of the multi-gang switch socket in FIG. 1;

FIG. 4 is a bottom view of the multi-gang switch socket in FIG. 1;

FIG. 5 is a top view of the multi-gang switch socket in FIG. 1;

FIG. 6 is a perspective view of the multi-gang switch socket in FIG. 1;

FIG. 7 is a front view showing the ON status of a multi-gang switch socket of a first embodiment;

FIG. 8 is a right side view of the multi-gang switch socket in FIG. 7;

FIG. 9 is a left side view of the multi-gang switch socket in FIG. 7;

FIG. 10 is a bottom view of the multi-gang switch socket in FIG. 7;

FIG. 11 is a top view of the multi-gang switch socket in FIG. 7;

FIG. 12 is a perspective view of the multi-gang switch socket in FIG. 7;

FIG. 13 is a front view showing the OFF status of a multi-gang switch socket of a second embodiment;

FIG. 14 is a right side view of the multi-gang switch socket in FIG. 13;

FIG. 15 is a left side view of the multi-gang switch socket in FIG. 13;

FIG. 16 is a bottom view of the multi-gang switch socket in FIG. 13;

FIG. 17 is a top view of the multi-gang switch socket in FIG. 13;

(Continued)

FIG. 18 is a perspective view of the multi-gang switch socket in FIG. 13;
 FIG. 19 is a front view showing the ON status of a multi-gang switch socket of a second embodiment;
 FIG. 20 is a right side view of the multi-gang switch socket in FIG. 19;
 FIG. 21 is a left side view of the multi-gang switch socket in FIG. 19;
 FIG. 22 is a bottom view of the multi-gang switch socket in FIG. 19;
 FIG. 23 is a top view of the multi-gang switch socket in FIG. 19;
 FIG. 24 is a perspective view of the multi-gang switch socket in FIG. 19;
 FIG. 25 is a front view showing the OFF status of a multi-gang switch socket of a third embodiment;
 FIG. 26 is a right side view of the multi-gang switch socket in FIG. 25;
 FIG. 27 is a left side view of the multi-gang switch socket in FIG. 25;
 FIG. 28 is a bottom view of the multi-gang switch socket in FIG. 25;
 FIG. 29 is a top view of the multi-gang switch socket in FIG. 25;
 FIG. 30 is a perspective view of the multi-gang switch socket in FIG. 25;
 FIG. 31 is a front view showing the ON status of a multi-gang switch socket of a third embodiment;
 FIG. 32 is a right side view of the multi-gang switch socket in FIG. 31;
 FIG. 33 is a left side view of the multi-gang switch socket in FIG. 31;
 FIG. 34 is a bottom view of the multi-gang switch socket in FIG. 31;
 FIG. 35 is a top view of the multi-gang switch socket in FIG. 31;
 FIG. 36 is a perspective view of the multi-gang switch socket in FIG. 31;
 FIG. 37 is a front view showing the OFF status of a multi-gang switch socket of a fourth embodiment;
 FIG. 38 is a right side view of the multi-gang switch socket in FIG. 37;
 FIG. 39 is a left side view of the multi-gang switch socket in FIG. 37;
 FIG. 40 is a bottom view of the multi-gang switch socket in FIG. 37;
 FIG. 41 is a top view of the multi-gang switch socket in FIG. 37;
 FIG. 42 is a perspective view of the multi-gang switch socket in FIG. 37;
 FIG. 43 is a front view showing the ON status of a multi-gang switch socket of a fourth embodiment;
 FIG. 44 is a right side view of the multi-gang switch socket in FIG. 43;
 FIG. 45 is a left side view of the multi-gang switch socket in FIG. 43;
 FIG. 46 is a bottom view of the multi-gang switch socket in FIG. 43;
 FIG. 47 is a top view of the multi-gang switch socket in FIG. 43; and,

FIG. 48 is a perspective view of the multi-gang switch socket in FIG. 43.
